United States Patent Office

Des. 181,519
Patented Nov. 26, 1957

181,519

SHUTTER

Robert O. Devereux, Los Angeles, Calif.

Application October 14, 1955, Serial No. 38,363

Term of patent 7 years

(Cl. D13—1)

Fig. 1

Fig. 2

Figure 1 is a front perspective view of a shutter, showing my new design; and,

Figure 2 is a back perspective view thereof.

The design for the shutter disclosed is characterized by the central portions having the configurations shown.

I claim:

The ornamental design for a shutter, as shown and described.
